UNITED STATES PATENT OFFICE.

LESLIE G. TROOD, OF NAPA, CALIFORNIA.

CLOSURE FASTENER AND OPERATING MEANS.

Application filed January 21, 1925. Serial No. 3,805.

This invention relates to what is known in the art as a closure fastener, and it has specific reference to an automatically operable latch and manually operable means for releasing it.

It is my object to generally improve upon a device of this class by providing one which is exceedingly simple in construction and such as to enable it to be especially adaptable to garage doors and the like.

The specific structure forming the invention and the advantages derived from its use will become apparent from the following description and drawing.

15 In the accompanying drawing forming a part of this application and in which like numerals are employed to designate like parts throughout the same:

Figure 1 is an elevational view, partly in section showing a fastener apparatus constructed in accordance with this invention, and the manner of associating the same with a swinging door.

20 Fig. 2 is a view showing substantially the same construction with the device applied to an inwardly swinging door.

Fig. 3 is a horizontal section through the lower portion of Fig. 1.

25 Fig. 4 is a detail elevational view of the manual operating means.

Inasmuch as the device is applicable to both inwardly and outwardly swinging doors mounted upon vertical pivots, and inasmuch as the construction is substantially the same in both instances except for proportions, it is thought that the description of the device seen in Figure 1 will be sufficient to uncover and render the device in Fig. 2 as clear and concise also. In proceeding accordingly it will be seen that the improvement includes an attaching bracket 1 which is intended to be attached to the door D. The bracket is preferably, as seen more clearly in Fig. 3, a small section of an angle iron and is riveted or otherwise securely fastened in place as shown. Pivoted between its ends upon the right angularly disposed wing of the bracket is a horizontally disposed latch 2, the pivotal connection being indicated at 3. At its free end this latch is equipped with an appropriately shaped head 4 adapted to take over or engage a keeper 5 fastened to a relatively stationary part. For an outwardly swinging door as shown in Fig. 1 the keeper may be secured to a post or the like P. The

keeper preferably consists of a small angle bracket attached at the inclination indicated so that one flange thereof is disposed in the path of movement of the width of 60 the latch.

In the case of the inwardly swinging door D as shown in Fig. 2 the keeper 5 will be attached to the wall of the garage. The attaching bracket is provided adjacent the inner end of the latch to the laterally projecting pin 6 forming a stop and this limits the swinging movement of the latch in one direction and insures that it will at all times be maintained in a substantially horizontal plane. Hence, it is ever-set to automatically snap over the keeper. While gravity may be relied upon to provide for this automatic snap action, I prefer to employ a relatively strong coiled spring 7, the same 75 being anchored at one end upon the adjacent end of the latch and fastened at its other end to the flange of the attaching bracket.

For operating the latch to release it I 80 utilize an arched mounting bracket 8 which is fastened to the inner surface of the door at the elevation indicated. A hand lever 9 is pivoted between its ends to the arch of the bracket, a pull cord 10 being fastened to the 85 outer end of the lever and depending therefrom but being anchored to the swinging latch 2 at a point adjacent its pivot.

Obviously, by exerting a downward push upon the right hand end of the lever seen 90 in Figure 4, an upward pull will be exerted upon the pull cord 10 and inasmuch as the point of connection of this cord is beyond the pivots, the latch will be lifted to disengage the same from the keeper, then 95 the door will be free to be swung closed. Normally the latch projects in the horizontal plane as shown and in the case of the outwardly swinging door, the latter is provided with a vertical slot to permit the headed end of the latch to extend through and beyond it. Consequently, when the door is swung open the latch will automatically engage the keeper in an obvious way to hold the door open.

100 It is desirable indeed to provide an exceedingly simple structure of this kind for application to garage doors and the like for by violently swinging the door open, it is unnecessary to carry it around in the usual way but to hook it, inasmuch as the spring actuated latch will automatically engage the

keeper and lock the door in an open position.

A comparatively light pressure upon the operating lever will lift the latch to permit the door to be again closed. Hence, when one is in a hurry, a device of this kind will be found exceedingly advantageous.

From the foregoing description and drawing, it is thought that a clear, comprehension of the invention may be had, and for this reason a more lengthy description is thought unnecessary.

While I have shown and described the preferred embodiments of the invention I wish it to be understood that minor changes coming within the field of the invention claimed may be resorted to if desired.

I claim:—

In a structure of the class described, an attaching bracket in the form of an angle

iron section, a latch pivoted between its ends upon one flange of said section, said latch provided at its outer end with a hook, a stop pin carried by said flange and cooperable with the latch for normally maintaining it in a horizontal plane, a spring attached at one of its ends to the inner ends of said latch and secured at its opposite end to said one flange, a keeper with which said hook is adapted to cooperate, an arched bracket adapted to be fastened to the closure at a point above said attaching bracket, an operating lever pivoted between its end upon said arched bracket, and a pull cord connected to one end of said lever and to the intermediate portion of said latch for operating the latter.

In testimony whereof I affix my signature.

LESLIE G. TROOD.
